UNITED STATES PATENT OFFICE.

GLENN E. HOFFMAN, OF SPRINGFIELD, ILLINOIS, ASSIGNOR TO HOFFMAN MANUFACTURING COMPANY, OF SPRINGFIELD, ILLINOIS, A CORPORATION OF ILLINOIS.

TRANSMISSION BAND.

Application filed March 5, 1923. Serial No. 622,912.

To all whom it may concern:

Be it known that I, GLENN R. HOFFMAN, a citizen of the United States, residing at Springfield, in the county of Sangamon and State of Illinois, have invented certain new and useful Improvements in Transmission Bands; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to transmission bands, and has for its object to provide improved features of construction in the removable ear of the band whereby it may be securely held to the band when applied and may be easily and expeditiously detached and removed to facilitate removal of the band from its drum, and its replacement, without interference from the associated parts of the transmission, as for instance, in the Ford type of transmissions for an automobile or truck.

To the accomplishment of the foregoing and such other features as may hereinafter appear the invention consists in the features hereinafter particularly described and then sought to be clearly defined by the claims, reference being had to the accompanying drawing forming a part hereof, and in which

Figure 1 is a perspective of the removable ear, detached;

Figure 2 a top plan view of the same, on a larger scale;

Figure 3 a vertical longitudinal section through the ear and a part of the transmission band;

Figure 4 a top plan of one end of the metallic band, with a part broken away;

Figure 5 a vertical longitudinal section through a portion of the ear, metallic plate and lining, showing an upturned flange on the metallic band to bear against the notched end of the ear.

In the drawing, the numeral 1 designates the removable ear of a transmission band, the shank portion of the ear being formed with slots 2 having enlarged end portions 3 and with a hole or opening 4 positioned adjacent to the notched end 5 of the ear. The transmission band as illustrated comprises a metallic band or strap 6 provided

as usual with a lining 7 of woven fabric or other suitable material, and in the present case provided with headed studs 8 designed to enter the slots 2 and with a stud or pin 9 designed to enter the hole or opening 4 formed in the ear so that it will lock the ear to the band at a point adjacent to the notched end of the ear and prevent the ear from moving either longitudinally or laterally. In placing the ear in position the headed studs 8 are inserted through the enlargements of the slots 2 and the ear then slid toward the free end of the band so as to bring the enlarged heads into the narrow portions of the slots with their heads overlapping the shank of the ear to prevent separation of the ear from the band. At the same time the hole or opening 4 in the ear is brought into alignment with the stud or pin 9 which snaps into the hole 4 and this prevents the ear from moving either longitudinally or laterally, and thus by this stud or pin and the headed studs the ear is held securely to the band. To remove the ear from the band, the metal strap or band at the notched end of the ear is pressed away from the ear by use of any suitable tool until the stud or pin 9 is disengaged from the hole 4 and then the ear is slid on the band to bring the headed studs into the enlargement of the slots 2 when the ear may be lifted from off the band and the latter is left free for proper manipulation for removal from the band drum without interference from parts of the transmission gear of the vehicle. The portion of the transmission band which has the other ear permanently attached thereto as usual in transmission bands is not illustrated as it is well known to the skilled in the art.

If desired, the end of the metallic band or strap 6 next to the notched end of the ear may be extended slightly beyond the ear and folded upwardly upon itself to form an abutment 10 as illustrated in Figure 5 against which the notched end of the ear will bear so that a firmer connection between the ear and band may be effected and any possible end play of the ear prevented.

Having described my invention and set forth its merits what I claim is:

1. A transmission band provided with a removable ear formed with slots having enlarged ends and an opening located adjacent to the notched end of the ear between it and

the adjacent slot, and a band provided with headed studs to fit in the slots of the ear and a stud or pin to fit in the opening adjacent to the notched end of the ear.

- 5 2. A transmission band provided with a removable ear formed with a slot having an enlarged end and an opening located adjacent to the notched end of the ear, and a band with a headed stud to fit in the slot of
10 the ear and a stud or pin to fit in the open-

ing adjacent the notched end of the ear, the end of the band having a portion thereof bent upwardly and folded to form an abutment for the end of the ear.

In testimony whereof I affix my signature ¹⁵ in presence of two witnesses.

GLENN R. HOFFMAN.
